TOBACCO PIPE

Kurt F. J. Kirsten, Seattle, Wash.

Application January 20, 1939, Serial No. 251,954

9 Claims. (Cl. 131—201)

This invention relates to tobacco pipes and is a continuation in part of my pending application for Letters Patent of the United States filed August 30, 1938, Ser. No. 227,483.

5 In order to clarify the objective ends to which the present invention is directed, it may be here stated that my above-identified pending application discloses the new combination of a metallic smoke barrel having a tobacco bowl of clay, briar or other suitable material detachably mounted thereon to lie in proximity of one end, the chamber of the barrel being in direct communication with the chamber of the bowl, and a non-metallic mouth-piece or bit detachably fitted to the opposite end of the barrel, said barrel chamber being of relatively large smoke capacity and being formed with a through-bore of which the end opposite the bit-receiving end is normally closed by a removable plug to permit a cleaning wad to be forced through the barrel for removing residual tars and other reduced condensable constituents of the tobacco smoke deposited on the walls of the smoke chamber.

The immediate adoption of this described pipe by the smoking public, especially when it is considered that the machined nature of the parts incident to precision manufacture entails a production expense necessarily reflected in a selling figure appreciably higher than that of even the finest pipes previously available, evidences not only a growing dissatisfaction by smokers of the characteristic tongue-bite, gurgling, and objectionable wet heel of the conventional pipe but also is a recognition of complete and lasting satisfaction by the large majority of those smoking my perfected pipe. There are, however, instances where individuals of nervous disposition take relatively strong and rapid puffs with the result that insufficient time is given the gases of combustion to properly cool in the chamber of the barrel. While it is true that the smoking pleasure to these few individuals is immeasurably greater than that which can be obtained from any other pipe, still it is short of the perfect smoke for which the pipe is designed and it is my aim to provide means which can, where necessary, be employed in the pipe to bring perfect smoking pleasure to even those individuals who by nature are unable to adapt themselves to the proper mode of pipe smoking. To accomplish this aim, the principal object of the present invention is to engineer a practical baffle into the bore of the barrel for deflecting the gases of combustion from their normal direct path to the mouth-piece, the circuitous route so obtained assuring added time in

which to transfer the heat of combustion and reduce the objectionable tars and oils from a volatile to a condensed form. It is a further and particular object to so adapt the baffle to the pipe as to maintain the ease of cleaning and other advantages characteristic of my peculiar form of pipe construction.

The invention resides in the novel construction, adaptation and combination of parts hereinafter described with reference to the preferred embodiment illustrated in the drawing and set forth in the claims hereto annexed.

In said drawing:

Figure 1 is a view in elevation representing the pipe. 15

Fig. 2 is a longitudinal vertical section showing one embodiment of the present invention in which the baffle is formed as an integral part of the closure plug.

Fig. 3 is a fragmentary transverse vertical section taken on line 3—3 of Fig. 2. 20

Fig. 4 is a top plan view detailing the plug shown in the preceding views.

Fig. 5 is a longitudinal vertical section indicating another embodiment of the invention in which the baffle is formed as an extension of a bit-piece fixedly carried by the bit; and 25

Fig. 6 is a fragmentary transverse vertical section taken on line 6—6 of Fig. 5.

The barrel 10 of my pipe is of Duralumin or other material relatively high in heat conductivity, said barrel being provided exteriorly with longitudinally extending fins 11 and having a cylindrical bore which is of uniform diameter for the greater portion of the barrel's length with the two ends slightly flared to provide sockets for the reception, at the front end, of a plug 12 and, at the rear end, of a mouth-piece 13. A smoke passage 14 is provided through the mouth-piece and is desirably prolonged into the chamber of the barrel by a tube 15. The bowl of the pipe is denoted by 16 and fits in a suitable socket provided at the forward end of the barrel, this socket being in the nature of a circular well having inclined side walls and formed with a centrally disposed and internally threaded upstanding neck 17 which extends into a bore formed in the base of the bowl, the bowl being secured in relation to its socket by a center-bored screw 18 which finds bearing engagement as between its head 18' and the bowl within a counter-bore of the latter, the lower limits of the counter-bore being slightly above the upper limits of the neck. 35

Said plug 12 is constructed in the form of a thimble having an external taper corresponding 40

55

to the flare of the socket therefor and is or may be of two-piece construction of which the sleeve portion 20 is given a fixed press-fit engagement within the circular recess of a knurled head 21, the latter being desirably of a non-conductive material such as Bakelite. The sleeve is of a length to extend into the bore of the barrel beyond the rear limits of the smoke port thereto and in its upper wall, circumferentially aligned 10 with a pointer 21' of the head 21, is formed with a longitudinal depression providing a smoke channel 22 which opens into the interior of the plug through a narrow throat 23 disposed adjacent the base or head wall of the plug. It will 15 be readily apparent that the described smoke channel serves to deflect the gases of combustion to direct the same against the head wall, the non-conductive nature of which prevents transmission of heat to the knurled edge. The plug 20 of course serves as a valve in response to rotary movement thereof for sealing the condensation chamber of the barrel against escape of liquid deposits through the smoke port into the bowl of the pipe, a provision which permits the pipe to 25 be safely carried in the pocket when not in use.

The modification shown in Figs. 5 and 6 represents a metal extension 25 fixed to the mouth-piece and in the assembled position of the latter arranged to snugly fit the wall of the barrel for 30 the greater portion of the barrel length, the forward end of this extension being depressed in the provision of a smoke channel 26 corresponding to the smoke channel 22. Lateral wings 27 are formed at each side of the depressed channel 35 in the transverse plane of the smoke port and functionally correspond to the concentric wall of the plug for lapping the smoke port in response to rotary movement of the mouth-piece.

The invention is believed clear from the foregoing description, it being considered obvious that structural modifications other than those illustrated may be resorted to without departing from the scope of the invention. I intend that the language employed in the hereto annexed claims be given an interpretation commensurate with the state of my advanced teachings and that no limitations be implied excepting where such limitations are necessarily introduced to the claims to distinguish from prior 50 knowledge in the art.

What I claim is:

1. In a tobacco pipe, in combination, a barrel formed with a through-bore operating as a condensation chamber for the gases of combustion, having a smoke port in the upper wall, and providing a tobacco-receiving chamber arranged in smoke-feeding relation to the smoke port, and removable closure devices for the opposite ends of said bore, one of said closure devices providing 55 an extension projecting into the bore and into lapping relation to the smoke port to act as a valve therefor, said extension providing a smoke conduit movable by rotation into registering relation with the smoke port and operating to divert smoke drawn through the latter into the forward end of the condensation chamber for causing said smoke to traverse a circuitous route in its passage through the chamber.

2. In a tobacco-pipe, in combination, a barrel 70 formed with a through-bore operating as a condensation chamber for the gases of combustion and having a smoke port in the upper wall, a tobacco-receiving bowl detachably mounted on the barrel in smoke-feeding relation to the smoke 75 port, a removable plug operating as a closure for

the front end of the bore, a mouth-piece detachably fitting the rear end of the bore, and an extension carried by the mouth-piece and extending forwardly therefrom into lapping relation to the smoke port, the lapping portion of said extension having a channel-forming depression therein movable by rotation into registering relation with the smoke port and operating to divert smoke drawn through the port into the forward end of the condensation chamber for 10 causing said smoke to traverse a circuitous route in its passage to the mouth-piece.

3. In a tobacco pipe, in combination, a barrel formed with a through-bore operating as a condensation chamber for the gases of combustion 15 and having a smoke port in the upper wall, a tobacco-receiving bowl mounted on the barrel in smoke-feeding relation to the smoke port, a mouth-piece detachably fitting the rear end of the bore, and a removable plug operating as a closure for the front end of the bore and formed with an extension projecting rearwardly 20 therein beyond the smoke port, said extension having a snug fit in relation to the wall of the bore modified by a channel-forming depression 25 arranged to register with the port and operating to divert smoke drawn through the port into the forward end of the condensation chamber for causing said smoke to traverse a circuitous route in its passage to the mouth-piece.

4. In a tobacco pipe, in combination, a barrel produced from a metal conducive to the radiation of heat and formed with a through-bore operating as a radiation chamber and having a smoke port in the upper wall, a tobacco-receiving bowl detachably mounted on the barrel in smoke-feeding relation to the smoke-port, a mouth-piece detachably fitting the rear end of the bore, and a rotary plug operating as a closure for the front end of the bore and formed to extend rearwardly 30 therein beyond the smoke port, said extended portion of the plug having a snug fit in relation to the wall of the bore modified by a longitudinal depression movable by rotation into and from registering relation with the port and operating 35 in its registering position as a smoke channel to divert smoke drawn through the port into the forward end of the radiation chamber for causing said smoke to traverse a circuitous route in its 40 passage to the mouth-piece.

5. The tobacco pipe defined in claim 4 wherein the plug is thimble-like in form and of two-piece construction of which the head wall is of Bakelite or other like or suitable material resistant to the conduction of heat.

6. In a tobacco pipe, in combination, a thin-walled barrel produced from a metal conducive to the radiation of heat with a through-bore of appreciable volumetric capacity operating as a condensation chamber for the gases of combustion 60 and having a smoke port in the upper wall, a tobacco-receiving bowl mounted on the barrel in smoke-feeding relation to the smoke port, a mouth-piece seating in the rear end of the bore and rotatable in relation thereto, a closure device 65 detachably fitting the forward end of the bore, and a thin-gauge metallic device for the smoke port fixedly carried by the mouth-piece and extending therefrom as a valve for the smoke port into the bore of the barrel, said valve device being movable by rotary movement of the mouth-piece from a normal position inoperative to the smoke port into closure relation thereto for trapping condensations within the condensation 70 75

chamber against admission through the smoke port to the tobacco bowl.

7. In a tobacco pipe, in combination, a barrel bored to form a condensation chamber for the gases of combustion and having a smoke port in the upper wall, a tobacco-receiving bowl mounted on the barrel in smoke-feeding relation to the smoke port, a mouth-piece detachably associated with the barrel, and an extension carried by the mouth-piece and extending therefrom longitudinally of the bore into lapping relation to the smoke port, the lapping portion of said extension having a channel-forming depression therein movable by rotation into registering relation with the smoke port and functioning, when so registered, to divert smoke drawn through the port into the forward end of the condensation chamber for causing said smoke to traverse a circuitous route in its passage to the mouth-piece.
8. In a tobacco pipe, in combination, a barrel formed with a through-bore operating as a condensation chamber for the gases of combustion, having a smoke port in the upper wall, and providing a tobacco-receiving chamber arranged in smoke-feeding relation to the smoke port, a mouth-piece functioning as a removable closure for one end of said bore, and a removable closure for the other end of the bore, one of said closures providing an extension projecting into the bore and into lapping relation to the smoke port to act as a valve therefor, said extension providing a smoke conduit movable by rotation into registering relation with the smoke port and operating to divert smoke drawn through the latter directly from the point of entry of said smoke to the mouth-piece for causing the smoke to traverse a circuitous route in its passage through the chamber.
9. In a tobacco pipe, in combination, a barrel formed with a through-bore operating as a condensation chamber for the gases of combustion, having a smoke port in the upper wall, and providing a tobacco-receiving chamber arranged in smoke-feeding relation to the smoke port, a mouth-piece seating in the rear end of the bore and rotatable in relation thereto, a closure device detachably fitting the forward end of the bore, and a thin-gauge metallic device for the smoke port fixedly carried by the mouth-piece and extending therefrom as a valve for the smoke port into the bore of the barrel, said valve device being movable by rotary movement of the mouth-piece from a normal position inoperative to the smoke port into closure relation thereto for trapping condensations within the condensation chamber against admission through the smoke port to the tobacco-receiving chamber.
